UNITED STATES PATENT OFFICE

1,974,487

TRIMMING MACHINE

Andrew Eppler, Lynn, Mass., assignor to United Shoe Machinery Corporation, Paterson, N. J., a corporation of New Jersey

Application January 10, 1933, Serial No. 651,015

17 Claims. (Cl. 12—82)

This invention relates to trimming machines and is herein illustrated as embodied in an in-seam-trimming machine of a type similar to that illustrated and described in Letters Patent of the

5 United States No. 1,680,494, granted August 14, 1928, on application of H. A. Ballard. An object of the present invention is to provide improvements by which the disposal of severed waste-materials will be facilitated.

10 In a machine of the type mentioned above a rotary, cup-shaped trimming cutter for severing strips of surplus materials from the bottoms of lasted shoes is arranged in the mouth or receiving end of a waste-pipe through which the strips 15 or scraps of severed material are conducted from the trimming cutter. In the operation of such a machine the severed strips enter the cavity in the trimming cutter and are deflected backwardly through the open mouth thereof to approach 20 the entrance to the waste-pipe, the longer strips being bent as they are deflected toward the receiving end of the waste-pipe.

In recognition of these conditions, and in accordance with a feature of the present invention 25 the trimming machine herein illustrated is provided with cutting means arranged to sever progressively a long strip of surplus material on the bottom of a lasted shoe, and with other cutting means arranged to snip the surplus material 30 periodically and thereby divide it into short sections adjacent to the point where it is severed. Such dividing of the surplus material facilitates not only deflection of the material from the severing cutter but also progress of the defected material into and through a waste-pipe; the more so if the material is stiff or if the severed pieces 35 would otherwise be so long and crooked as to clog the pipe.

40 Preferably, and as herein illustrated, the point at which the snipping occurs is slightly in advance of the point where the severing occurs, since the surplus material will be under better control before being severed from a shoe than afterward. Moreover, although the snipping cuts could, if desired, intersect the line of severance, the invention, in the embodiment herein illustrated, provides for adjusting the snipping means to leave a little unsnipped material by which the sections of a severed strip will remain connected in a train 45 but still be so nearly individual as to be capable of individual deflection.

The expression "lasted shoe" as used herein is intended to include a shoe of any type that has been lasted but not outsoled or turned. For example, a welt-shoe that has been inseamed but

not outsoled would not only be within the scope of that term but would require trimming to sever the surplus overdrawn upper material provided for lasting. Then, too, certain types of cemented lasted shoes have surplus overdrawn upper material and insole-lips provided for lasting, both of which require to be severed before an outsole can be laid. In many cases the layers of surplus materials thus lasted contain lasting cement which not only binds them together but also renders the severed strips stiff.

As in the machine illustrated in the Letters Patent above mentioned, the machine herein illustrated is provided with a tubular member arranged to conduct the severed materials from the severing cutter; the tubular member is arranged to rotate about its axis to feed the work past the cutter; and the work-feeding surface of the tubular member is horizontal and arranged to operate on the margin of the upturned bottom of a lasted shoe. Nevertheless, the axis of the tubular member is steeply inclined in the machine herein illustrated. Moreover, since proper guidance and feeding of a shoe require contact of the tubular member with the bottom of the shoe, and since the bottom should be nearly, if not quite, level to enable the operator to observe it and to manipulate the shoe according to its curvatures, the tubular member herein illustrated is provided with a flared work-feeding surface the flare of which 85 counteracts the inclination of the axis of the member. Thus, the present invention provides also for utilizing the force of gravity to expedite the progress of the waste-products through the tubular member without putting the operator 90 under any disadvantage with regard to observing or manipulating the work.

Other novel features of improvement are illustrated in drawings and hereinafter described and claimed.

Referring to the drawings:

Fig. 1 is a front elevation of a trimming machine constructed in accordance with the present invention;

Fig. 2 is a right side elevation thereof, partly in vertical section;

Fig. 3 is a bottom plan view of a typical lasted shoe of the welt type, a welt having been attached thereto by inseam stitches;

Fig. 4 is a view similar to Fig. 2 of the operating parts in the vicinity of the trimming locality;

Fig. 5 is a horizontal section through the structure intersected by line V—V of Fig. 4; and

Fig. 6 is a fragmentary sectional view similar to the lower portion of Fig. 4 but representing the

snipping cutter at the opposite limit of its range of travel.

The lasted shoe represented in Figs. 3, 4 and 6 comprises the usual upper 10, insole 11, welt 12, 5 and inseam stitches 13, the latter extending through the welt, the upper and the between substance 14 of the insole. A last 15 is represented in Figs. 4 and 6.

In a shoe of this type the upper 10 (which 10 commonly includes a lining) is cut initially to provide surplus material for lasting purposes. As a result of the lasting operation, the margin 16 of surplus upper material projects from the bottom of the insole 11 and lies against the between substance 14 of the insole. Moreover, this margin 16 of surplus upper material and commonly also the between substance 14 of the insole remain as represented in the drawings until after the inseam stitches 13 have been sewn to attach the welt 12 and to form a permanent connection between the upper and the insole, but before an outsole can be laid it is necessary to sever the upstanding between substances 14 and 16 nearly but not quite to the level of the inseam stitches 13. A narrow 20 strip of the welt 12 may also be severed incidentally to severing the substances 14 and 16 as above described.

This operation, which, in the case of a welt shoe, is commonly known as inseam-trimming, is 30 begun at a point indicated at 17 in Fig. 3 and progresses lengthwise of the shoe to and around the toe-end and thence along the opposite side to a corresponding point indicated at 18. The surplus materials to be thus severed commonly include as many as five layers in the shank-portion 35 and in the ball-portion, and may include from one to three additional layers at the toe-end where many shoes are provided with tips and toe-stiffeners impregnated with a sticky compound comprising wax and asphaltum. Irrespective of the 40 number of layers thus severed, it is common to sever them in such a way as to produce one continuous strip coextensive with the total range of trimming. Such a strip is not only long and 45 crooked but is in many cases so thick and stiff as to involve difficulty with regard to its disposal not only while the severing is in progress but thereafter.

The general organization of the machine herein 50 illustrated is similar to that illustrated in United States Letters Patent No. 1,169,070 granted January 18, 1916 on an application filed by me. As in my former machine the present machine comprises a rotary cup-shaped cutter 20 for severing the surplus materials hereinbefore described, this 55 cutter being frusto-conical and provided with an endless cutting edge 21 that is circular except that it is preferably divided into many small scallops that are readily apparent when viewed as in Figs. 1 and 5. The illustrated organization is such that the cutter 20 rotates about a horizontal axis in the direction indicated by an arrow 22 in Fig. 4, the open end or cutting edge 21 being at the right and the closed end at the left. Consequently, in 60 operation, the shoe must be fed from right to left. The strip of severed materials enters the cutter and impinges against the holder or stock by which the cutter is supported and driven.

As illustrated in Fig. 5, the holder or supporting stock for the cutter comprises a circular disk 23, a sleeve 24, and a circular clamping disk 25, the latter being provided with an internal screw-thread 26 that engages a complementary screw-thread on the sleeve 24 to clamp the rear end of 75 the cutter against the circular disk 23. These

parts constituting the holder are mounted upon a stationary stud 27 relatively to which they may rotate.

A segment of the cutter 20 is nested in an annular bell-mouthed member 28 screwed into 80 and forming the receiving end of a tubular, down-draft nozzle 29 which constitutes a section of a pneumatic suction-pipe through which air may be drawn by a fan or blower (not shown) to carry away waste-pieces severed from shoes. 85 The direction of rotation of the cutter 20 is such as to throw dust and chips into the nozzle 29. Moreover, the nozzle 29 is rotated about its axis to feed a lasted shoe past the cutter 20, but, unlike the corresponding nozzle shown in the aforesaid Ballard patent, its axis is steeply inclined to utilize the force of gravity for assisting the waste-pieces therethrough.

The bell-mouthed member 28 constitutes a feed- 90 roll for operating on the margin of the upturned bottom of a shoe, and the flare of its external surface 30 counteracts the inclination of the nozzle 29, to the end that the portion that overlies and acts on the margin of the shoe will be substantially horizontal. As shown, this flared work-feeding surface 30 is scalloped to provide 95 fine work-feeding teeth. When operating on a welted shoe the surface 30 cooperates with a freely rotatable supporting roll 31 to clamp the welt, the roll 31 being normally raised by a spring 100 to apply the clamping pressure but being de- 105 pressible by manually-operated means to facilitate the introduction of a welt.

As shown in Figs. 1 and 2, the means for sup- 110 porting and controlling the roll 31 comprise a post 32, a vertically movable slide 33, a compression spring 34, a lever 35, and a rod 36 pivotally connected to the lever and extending downwardly to a treadle (not shown). The post 32 is mortised 115 into the slide 33 with cooperative dove-tail formations (Fig. 1) that provide for adjusting it forward and back as may be necessary to place the roll 31 in the most desirable cooperative relation to the feed-roll 28. Moreover, the dovetail portion of the slide 33 is divided by a kerf 37 and is provided with a bolt 38 by which it may be contracted to clamp the post 32. The slide 33 is 120 arranged in a guiding fixture 39 secured to the head or frame 40 by screws 41. The spring 34 is seated on a screw 42 by which its applied force 125 may be regulated, the screw having threaded connection with a portion of the fixture 39. The upper portion of the spring extends into a socket 130 formed in the slide 33 and applies its force upwardly against the upper end of the socket. To prevent the roll 31 from engaging the scalloped surface 30 when no welt is between them, the slide 33 is provided with an adjustable stop-screw 43 arranged to abut against a finger 44 formed on the fixture 39. When the lever 35 is depressed, its forward end engages a lug 45 formed on the slide 33 to separate the roll 31 from the feeding 135 member 28.

As shown in Fig. 2, the nozzle 29 is rotatably 140 mounted in a bearing formed in the head or frame 40, its lower end being fitted into a fixed section 46 of the waste-pipe, the connection being such that although the nozzle 29 may rotate while the section 46 remains stationary no appreciable leakage of air occurs at the joint. Between its ends the nozzle 29 is provided with a worm-gear 47 by which it may be driven to feed the work, a worm 47 for this purpose being affixed to a shaft 48 journaled in the head 40. The 145 150

shaft 48 is provided with a pulley 49 on which a belt may run to operate the machine.

A cutting edge 50 (Figs. 4, 5, and 6) for dividing the strips of surplus materials 14, 16 into short sections is formed at one end of an arcuate blade 51. This blade has a dove-tail cross-section (see Fig. 5) and is thus adapted to be controlled and guided in a curvilinear path by a correspondingly curved dove-tail groove formed in a cutter-guard 52 that lies close to the circular cutting edge 21 and covers a large segment of the open end of the rotary cutter 20. The cutter-guard 52 also causes the stream of air approaching the nozzle 29 to flow first into the cavity in the cutter 20. The shank of the blade 51 carries a pivot stud 54 by which it is connected to an operating link 55. The link engages a wrist-pin 56 carried by a continuously driven gear 57 to which rotation is communicated by a train of connections hereinafter described.

When the blade 51 is fully retracted, as shown in Figs. 2, 4 and 5, it is entirely out of the path of the materials 14 and 16 being severed by the cutter 20, but when the blade is moved forward by the wrist-pin 56 its cutting edge 50 intersects the materials 14 and 16 to snip or divide them into short sections.

The surplus materials 14 and 16 are braced against the frictional drag of the rotary cutter 20 and against the thrust of the snipping blade 51 by a hardened steel cutting block 60 having a shearing edge with which the snipping edge 50 cooperates. The block 60 is rigidly secured to a fixture 61 (Fig. 5) that covers a large segment of the mouth of the waste-nozzle 29 to conserve the force of the pneumatic suction and to concentrate its effect at the point x where the waste products pass from the mouth of the cutter 20 into the nozzle. Since the fixture 61 and the cutter-guard 52 are both arranged adjacent to the mouth of the cutter 20, and since they and other elements hereinafter described cover nearly all the area of the mouth, they compel the stream of air that enters the waste-pipe to flow first into the cavity of the cutter 20 before it reaches the point x where the waste products are discharged from the cutter. It is thus assured that the waste products will be promptly withdrawn from the trimming cutter.

The narrow gap between the cutting block 60 and the cutter-guard 52 provides a channel through which the surplus materials 14 and 16 and some of the ingoing air may pass to enter the trimming cutter 20. Since the snipping cutter 50 is slightly in advance of the cutting edge 21, the surplus materials 14 and 16 will be divided into short sections before they are severed from the shoe and they will therefore remain under suitable control with respect to their presentation to both cutters.

The gap above referred to is occupied by an auxiliary feed-roll 62 that engages the insole 11 in the angle formed by the upstanding lip 14. This roll is not only driven in the direction required to feed the shoe but is spring-pressed toward the annular feed-roll 28 with which it cooperates to grip all the materials that pass between them. As shown in Fig. 4, the feed-roll 62 is screwed on the lower end of a spindle 63 by which it is carried, the spindle being journaled in a bearing member 64. The member 64 is carried by the cutter-guard 52 and secured thereto by a clamping bolt 66 with provision for adjustment lengthwise of the axis of the spindle 63.

The cutter-guard 52 is adjustably secured to yield to this shifting movement but being

to a swinging head 65 by clamping bolts 67, the holes 68 through which the bolts extend being elongated to provide for adjusting the guard 52 up and down as may be necessary to place it in the desired relation to the rotary cutter 20. Since the snipping cutter 51 is carried by the cutter-guard 52, its cutting end will necessarily partake of this adjustment and may, if desired, be positioned at a relatively low level to locate the snipping cuts so that they will intersect the line on which the surplus materials will be severed. Thus, the short sections of the severed materials may be entirely divided one from another. On the other hand, the cutter-guard 52 may be adjusted to locate the cutting edge 50 of the snipping cutter entirely above the line along which the surplus materials will be severed, and thus provide for dividing the materials into short sections that will remain connected in a train by slender, but easily flexible, uncut portions of the severed strip.

The swinging head 65 is hung on fixed trunnions 70 (Fig. 1) mounted in the upper part of the head or frame 40. The right-hand trunnion is tubular and provides a bearing for a driven shaft 71 (Fig. 2) by which rotation is communicated to the auxiliary feed-roll 62 and to the gear 57 that carries the wrist-pin 56 for operating the snipping cutter. An arm 72 (Fig. 2) is affixed to the swinging head 65 and extends to the rear where it is engaged by a compression spring 73 that normally maintains the auxiliary feed-roll 62 in position to clamp the surplus materials 14 and 16 of a shoe against the cutting block 60. Moreover, the arm 72 is connected with the lever 35 by a link 74, the effect of which is to retract the auxiliary feed-roll 62 and the snipping cutter 51 from the feed-roll 28 when the treadle is operated to depress the supporting roll 31.

Rotation for driving the auxiliary feed-roll 62 is derived from the shaft 48 (Figs. 1 and 2) through a train of connections comprising the following parts: spur-gear 75, spur-gear 76, shaft 77, helical gear 78, helical gear 79, shaft 80, helical gear 81, helical gear 82, shaft 71, worm 83, worm-gear 84, shaft 85, helical gear 86, and helical gear 87, the latter being affixed to the spindle 63 (Figs. 2 and 4).

Rotation for operating the wrist-pin 56 is derived from the shaft 85, the gear 57 being provided with helical teeth that cooperate with a helical gear 88 carried by the shaft 85.

Rotation for operating the rotary cutter 20 is derived from the spur-gear 76 through a driving train comprising spur-gears 90, 91 and 92, the latter being affixed to the sleeve 24 that carries the rotary cutter.

In keeping with the organization shown in Patent No. 1,169,070 the machine herein illustrated is provided with an abrading wheel 100 (Figs. 1 and 2) arranged to sharpen the rotary cutter 20, and with means for adjusting this cutter to counteract its loss of length in consequence of being sharpened. Rotation for driving the abrading wheel 100 is derived from a continuously driven clutch-pulley 101 over which a driving belt 102 runs. The transmission train comprises a complementary clutch-pulley 103, a belt 104, and a pulley 105 on the shaft 106 that carries the abrading wheel. A manually operated shipper 109 is arranged to shift the pulley 101 axially to the left (Fig. 1) to establish the clutched relation, the pulley 103 being arranged to yield to this shifting movement but being

backed by a compression spring 107 that furnishes the necessary pressure of the clutching faces one against the other to insure transmission.

The shaft 106 that carries the abrading wheel 5 is journaled in an adjustable support 110 (Fig. 2) by which the grinding wheel may be adjusted toward and from the cutter 20. For this purpose the support 110 is engaged by a screw-shaft 111 to which rotation is imparted by helical gears 10 112 and 113, the latter being carried by a shaft 114 provided with a hand-wheel 115.

To provide for adjusting the rotary cutter 20 as its length is reduced by the abrading wheel, the cutter-supporting stud 27 (Fig. 1) is affixed 15 to an adjustable slide 116 the upper portion of which has tongue-and-groove connection with a guideway 117 formed on the head 40. A screw 118 provided with a hand-wheel 119 engages an internal screw-thread in the slide 116 to afford 20 convenient adjusting means.

Having fully described my invention, what I claim as new and desire to secure by Letters Patent of the United States is:

1. A trimming machine comprising cutting 25 means arranged to sever progressively a long strip of surplus upper material on the bottom of a lasted shoe, and cutting means arranged to snip such surplus material periodically and thereby divide it into short sections.

30 2. A trimming machine comprising cutting means arranged to sever progressively a long strip of surplus upper material on the bottom of a lasted shoe, and cutting means arranged in advance of the severing locality to snip such 35 surplus material periodically and thereby divide it into short sections while it is still attached to the shoe.

3. A trimming machine comprising cutting means arranged to sever progressively a long 40 strip of surplus upper material on the bottom of a lasted shoe, a pair of cooperative shearing cutters arranged to snip such surplus material adjacent to the trimming locality, and mechanism for relatively moving said shearing cutters periodically to divide the surplus material into a series of short sections.

4. A trimming machine comprising a trimming cutter arranged to sever progressively a long strip of material of a work-piece, mechanism arranged 50 to operate said cutter with movement lengthwise of its cutting edge to execute a draw-cut, and power-operated cutting means arranged to snip said strip of material periodically adjacent to the severing locality.

55 5. A trimming machine comprising power-operated cutting means arranged to sever progressively a long flange of material projecting from a work-piece, and power-operated cutting means arranged adjacent to and ahead of the 60 severing locality to snip said flange of material periodically and thereby divide it into short sections.

6. A trimming machine comprising a cutter 65 having a cutting edge arranged to sever a flange projecting from a work-piece, mechanism arranged to operate said cutter with motion lengthwise of said edge, and power-operated cutting means arranged to snip periodically the flange on which said cutter is operating.

7. A trimming machine comprising cutting 70 means arranged to sever progressively a long strip of surplus upper material on the bottom of a lasted shoe, a cutter arranged to snip such material adjacent to the trimming locality with-

out cutting entirely through it, and mechanism arranged to operate said cutter periodically.

8. A trimming machine comprising a cutter arranged to snip a strip of surplus upper material secured to and projecting from the insole of a lasted shoe, mechanism arranged to operate said cutter periodically and power-operated cutting mechanism arranged to sever the snipped material from the shoe progressively as the shoe is fed past said snipping cutter.

85 9. A trimming machine comprising a rotary driven cutter having an annular cutting edge arranged to sever progressively a long strip of surplus upper material on the bottom of a lasted shoe, a member arranged to brace said material against the frictional drag of said cutter, said member having a shearing edge, and a reciprocatory cutter arranged to cooperate with said shearing edge periodically to snip said material at intervals.

90 10. A trimming machine comprising a stationary cutting block arranged to engage surplus upper material standing up on the bottom of a lasted shoe, a driven roll arranged to feed the shoe past said cutting block, a reciprocatory cutter arranged to cooperate with said cutting block periodically to snip said material at intervals, and power-operated cutting means arranged to sever the material so snipped.

100 11. A trimming machine comprising a pneumatic suction-pipe for carrying away waste-pieces severed from a lasted shoe, a reciprocatory cutter and a rotary annular cutter both arranged in a stream of air about to enter said pipe, the one to snip and the other to sever surplus upper 110 material on the bottom of the shoe, and mechanisms for operating said cutters simultaneously.

115 12. A trimming machine comprising a steeply inclined down-draft pneumatic suction-pipe for carrying away waste-pieces severed from a lasted shoe, two cutters arranged adjacent to the receiving end of said pipe, one to snip and the other to sever surplus upper material on the bottom of the shoe, and mechanisms for operating said cutters simultaneously.

120 13. A trimming machine comprising two cooperative feed-rolls arranged to grip surplus materials projecting from the bottom of a lasted shoe, a movable support by which one of said feed-rolls is carried toward and from the other, 125 a cutter carried by said movable support for snipping the surplus material adjacent to the bite of said feed-rolls, mechanism for operating said snipping cutter, a cutter arranged to sever the snipped materials adjacent to the snipping 130 locality, and means for operating said severing cutter.

14. A trimming machine comprising means arranged to guide and feed a lasted shoe, means arranged to snip surplus materials projecting 135 from the bottom of the shoe, means arranged to sever the snipped materials, and provisions for relatively adjusting said snipping means and said severing means to regulate the relation of the snipping cuts and the severing cut.

140 15. A trimming machine comprising a tubular member through which dust and chips may gravitate, the axis of said member being steeply inclined and said member being arranged to rotate about said axis and having a flared annular surface at its upper end the flare of which counteracts the inclination of said axis so that a portion of said surface may overlie and engage the margin of the upturned bottom of a lasted shoe, cutting means arranged adjacent to the upper end 145 150

of said tubular member to sever surplus upper material on the bottom of the shoe, mechanism for operating said cutting means, and means for rotating said tubular member to feed the shoe to said cutting means.

16. A trimming machine comprising a tubular member through which dust and chips may gravitate, the axis of said member being steeply inclined and said member being arranged to rotate about said axis and having a flared annular surface at its upper end to feed a lasted shoe by engagement with the margin of the upturned bottom thereof, a rotary cutter arranged to sever surplus material on the bottom of the shoe and

to throw dust and chips into the upper end of said member, and means for rotating said tubular member to feed the shoe to said cutter.

17. A trimming machine comprising two co-operative feed-rolls arranged to grip surplus upstanding materials forming a seam on the bottom of a lasted shoe, a rotary cutter arranged to sever surplus materials that have passed between said rolls, an inclined tubular member by which one of said feed-rolls is carried and through which the severed waste-products may gravitate from said cutter, and means for rotating said tubular member to operate said one of the feed-rolls.
